UNITED STATES PATENT OFFICE.

JOHN D. MILLER, OF JACKSON, MICHIGAN, ASSIGNOR OF ONE-HALF TO A. D. McBURNEY
AND ONE-HALF TO H. L. HITCHCOCK, BOTH OF JACKSON, MICHIGAN.

ARTIFICIAL REED.

1,169,178.

Specification of Letters Patent. Patented Jan. 25, 1916.

Application filed December 4, 1914. Serial No. 875,504.

To all whom it may concern:

Be it known that I, JOHN D. MILLER, a citizen of the United States of America, residing at Jackson, in the county of Jackson and State of Michigan, have invented certain new and useful Improvements in Artificial Reeds, of which the following is a specification, reference being had therein to the accompanying drawings.

10 The invention relates to artificial reeds designed for use in the manufacture of furniture and other articles, such for instance as baby carriages, baskets, etc., as a substitute for the natural reed. It is the object 15 of the invention to obtain a construction which not only presents a similar appearance to the natural product but also may be manipulated with equal facility during the manufacture of the product.

20 In the drawings: Figure 1 is an elevation of my improved artificial reed; Fig. 2 is a section showing the reed as woven in a fabric; Fig. 3 is a plan view of a slightly modified fabric; and Fig. 4 is a section there- 25 through.

My improved artificial reed comprises essentially a resilient metallic core and a spiral wrapping of fibrous material, such for instance as paper.

30 Heretofore non-resilient metallic wires have been covered with spiral wrappings, as for instance in the manufacture of stems for artificial flowers. Such a product cannot, however, be substituted for a reed in 35 the weaving of a fabric, for the reason that there will be no lateral tension upon the crossing strands, whereas with the natural reed there is sufficient resiliency to produce such a tension. I have therefore devised

40 a construction in which the core is formed of resilient material, such as piano wire. As shown, A is the resilient core and B the spiral wrapping of paper.

C is a fabric formed by weaving the arti-

ficial reeds, and as shown at D whenever a strand is bent the resiliency of the core will tend to force it back into the original position, as indicated by dotted lines at D'. This will place a lateral tension upon the crossing strands, indicated by the letter E, 50 with a result that the fabric will retain its form and will operate the same as fabric formed of natural reeds.

As shown in Figs. 3 and 4, a fabric may be formed in which the warp F is of larger 55 diameter than the woof G, both being formed of my improved artificial reed. With this fabric the warp is substantially straight in the completed article, but its resilient core facilitates bending forward 60 and backward during the weaving operation, as indicated in dotted lines in Fig. 4.

What I claim as my invention is:—

1. An artificial reed, comprising a resili- 65 ent core and a spiral wrapping of fibrous material thereon.

2. An artificial reed, comprising a core 70 formed of a resilient metallic wire, and a spiral wrapping of fibrous material covering said core.

3. A woven fabric formed of interlaced 75 strands each comprising a resilient metallic core, and a spiral wrapping of fibrous material.

4. A woven fabric comprising interlaced 80 warp and woof strands exerting a lateral tension upon each other, each formed of a resilient core and a spiral wrapping of fibrous material, said warp strands being of larger diameter than the woof strands and being substantially straight.

In testimony whereof I affix my signature in presence of two witnesses.

JOHN D. MILLER.
